SKIMMING DEVICE FOR BESSEMER CONVERTERS, LARGE LADLES, AND THE LIKE

Harry L. McFeaters, New Castle, Pa., assignor to Pennsylvania Engineering Corporation, a corporation of Pennsylvania

Application May 14, 1948, Serial No. 27,078

6 Claims. (Cl. 266—37)

1

This invention relates to slag skimmers for tiltable Bessemer converters and large tiltable ladles or the like and an object of this invention is to produce an improved slag skimmer for such vessels.

Another object is to produce an improved water cooled slag skimmer for tiltable Bessemer converters, large tiltable ladles and the like.

Another object is to produce an improved hydraulically operated slag skimmer for tiltable Bessemer converters, ladles and the like.

A still further object is to produce an improved hydraulically operated water cooled slag skimmer for tiltable Bessemer converters, ladles and the like.

A still further object is to produce an improved water cooled slag skimmer for tiltable Bessemer converters, that can be operated at a safe distance from the converter.

These and other objects which will be apparent to those skilled in this particular art, I attain by means of the structures described in the specification and illustrated in the drawings accompanying and forming part of this application.

In the drawings:

Figure 1 is a view mainly in side elevation of a tiltable Bessemer converter equipped with a slag skimmer embodying this invention and this view shows the skimmer in operation during pouring of the molten metal from the converter to a ladle;

Fig. 2 is a view similar to Figure 1 of the converter and shows the skimmer holding back the slag after all of the molten metal has been poured;

Fig. 3 is a view similar to Figs. 1 and 2 of the converter in upright or blowing position. This view shows the skimmer member moved to position outside of the converter;

Figs. 4 and 5 are outside elevational views of the converter in upright position and these views show the position of the skimmer and its operating mechanisms when the skimmer is not in use;

Fig. 6 is a view partially in elevation and partially in section looking toward the mouth of the converter when the converter is in the position shown in Fig. 2 and discloses the skimmer support means, the water cooling system and the piping for the hydraulic skimmer operating devices;

Figs. 7 and 8 are sectional detail views of parts of the skimmer mechanism; Fig. 8 being taken on line VIII—VIII of Fig. 6;

2

Fig. 9 is a top sectional view of the skimmer and that part of its support mechanism to which it is rigidly attached;

Fig. 10 is an elevational view of the mechanism for swinging the support frame and skimmer toward and from the mouth of the converter;

Fig. 11 is an elevational view of the mechanism for adjusting the position of the skimmer with relation to the level of the metal content of the converter;

Fig. 12 is a sectional view taken on line XII—XII of Fig. 11;

Fig. 13 is a sectional view taken on line XIII—XIII of Fig. 10;

Fig. 14 is a sectional view taken on line XIV—XIV of Fig. 10; and

Fig. 15 is a diagrammatic view of the hydraulic system which forms a part of the skimmer mechanism.

The device of this invention is carried by and becomes part of the converter in connection with which it is to be used and comprises a skimmer or slag hold-back blade or member, means for mounting the same for swinging movement into and from the mouth of the converter, means for adjusting the skimmer member with relation to the level of the metal content of the converter, means for circulating cooling water through the skimmer, and control valves by means of which the device is operated.

Two pads 20 and 21 secured to the shell of the nose of the converter adjacent the converter mouth are each provided with an outwardly extending boss 22. Within the boss of pad 20 a stub shaft 23 is rigidly secured while a stub shaft 24 is rigidly secured within the boss of pad 21. These stub shafts form supports upon which side members 25 and 26 of the mounting means for the skimmer member of the device are mounted for swinging movement.

The skimmer member, which is numbered 27, is made of suitable metal, is hollow, and by means of tubular connecting members 28 and 29 is joined to a tubular member 30 which connects the outer ends of side members 25 and 26.

Side members 25 and 26 in conjunction with tubular connecting member 30 constitute a supporting frame for skimmer 27, and such frame is pivotally connected to the converter by means of stub shafts 23 and 24.

The openings in side members 25 and 26 for receiving the stub shafts are provided with suitable bearing bushings 31.

55 A gear 32 is mounted on and secured to a tu-

tular portion 33 which extends laterally from side member 25 and surrounds a tubular extension of bushing 31. An annular member 34 serves as an abutment member and is secured to shaft 23 by means of a wedge key 35 which is driven into a hole formed for its reception adjacent the end of such shaft 23. A bearing washer 34a is mounted on shaft 23 between abutment member 34 and the adjacent end of gear 32. A washer 36 on shaft 24 is held in place by means of a wedge key 37 which is driven into a hole formed for its reception in shaft 24.

Tubular end member 30 of the support frame is built up at its ends by sleeves 38 which are preferably welded in place as shown at 39 in Fig. 7; this being an enlarged view of the end at the right side of Fig. 6.

These thickened ends of member 30 are journaled within bearing bushings 40 secured within openings in the outer ends of side members 25 and 26.

Sleeve 38 at the right-hand side of Fig. 6 has a gear 41 keyed thereto and a nut 42 threaded to such sleeve as at 43 prevents key 44 from working out of its slot in gear 41.

The frame which supports skimmer member 27 and which is mounted for swinging movement about stub shafts 23 and 24, is swung, in carrying the skimmer member into and from the mouth of the converter, by the hydraulically operated mechanism of Figs. 10, 13 and 14.

This mechanism comprises an hydraulic cylinder 45 carried by pads 46 and 47 secured to the converter shell between one of the converter trunnions 48 and the converter mouth. Cylinder 45 contains a piston 49 (Fig. 15) to which a piston rod 50 is attached. A rack 51 carried by piston rod 50 meshes with gear 32 and is therefore adapted, as it is reciprocated, to swing the skimmer support frame about stub shafts 23 and 24 into and from operative position.

Tubular member 30 which is provided with hollow branches 28 and 29 to the outer ends of which skimmer member 27 is secured, as before pointed out, is mounted for rotation with relation to frame side members 25 and 26 and carries gear 41 which is keyed to one of its sleeves 38. Tubular member 30 is rotated in order to adjust the position of skimmer member 27 with relation to the level of the metal content of the converter during pouring operations and such rotation, and therefore such adjustments, are obtained by means of the hydraulically operated mechanism disclosed in Figs. 11 and 12.

This mechanism comprises an hydraulic cylinder 52 which is carried by brackets 53 secured to side member 26 of the skimmer member mounting frame. Cylinder 52 contains a piston 54 (Fig. 15) to which a piston rod 55 is attached. A rack 56 carried by piston rod 55 meshes with gear 41 and is therefore adapted, as it is reciprocated, to rotate tubular member 30 to adjust the position of the skimmer member 27 with relation to the level of the metal content of the converter during pouring operations, as before pointed out.

Cylinders 45 and 52 are under the control of four-way valves 57 and 58 respectively.

Oil under pressure is supplied to cylinders 45 and 52 by a pump 59 driven by a motor 60. A tank 61 receives the oil discharged from cylinders 45 and 52 and pump 59 draws its supply of oil from tank 61 through line 61a. The lines between valve 57 and the opposite ends of cylinder 45 are numbered 62 and 63 while those between

valve 58 and the opposite ends of cylinder 52 are numbered 64 and 65. The lines between valves 57 and 58 returning oil to tank 61 are numbered 66 and the pressure lines between pump 59 and valves 57 and 58 are numbered 67.

If desired, pump 59 instead of discharging directly into lines 61 may discharge into a pressure tank or an accumulator and one or the other of these as the case may be, under the control of valves 57 and 58, would discharge to pressure line 61. A starter switch for motor 60 may be under the control of valves 57 and 58 or, if a pressure tank is employed, a pressure responsive switch may be used to operate the motor when the pressure therein falls below a predetermined point.

Lines 64 and 65, in line with the axes of stub shafts 23 and 24 and also in line with the axes of trunnions 48 of the converter are provided with swivel joints 69 of any desired type. Ball bearing swivel joints such as made by Chiksan Company, Brea, California, and Barco Swivel Joints manufactured by Barco Mfg. Company of Chicago, Ill., have been found satisfactory.

Lines 62 and 63, in line with the axes of trunnions 48 of the converter are provided with swivel joints 70 similar to joints 69.

During operation of the converter, as well as during pouring, cooling water is circulated through skimmer member 27 and tubular support 30 by means of inlet piping 71 and exhaust piping 72. Inlet piping 71 connects with a suitable source of supply (not shown) of cooling liquid, such as cooling water. The inlet piping includes a length of pipe 73 which parallels side member 25 of the support frame for the skimmer, and is rigidly attached thereto by a brace 74. At one end pipe 73 is provided with a swivel joint 75 which connects it with the interior of tubular member 30 and at its opposite end it is provided with a swivel joint 76 in line with the axes of stub shafts 23 and 24. This piping also includes a section of pipe 77 which is connected to pipe 71 by means of a swivel joint 78 which is in line with the axes of trunnions 48 of the converter. Outlet piping 72 includes a section of pipe 79 similar to section 73 of the inlet piping and this by a brace 74 is rigidly connected to swing with frame side member 26. This section 73 is also supplied with swivel joints at its opposite ends.

The outlet piping also includes a section 80 similar to section 77 which is also equipped with swivel joints at its ends in line with the axes of stub shafts 22 and 23 and the axes of the converter trunnions 48.

The piping for conveying pressure fluid to and from cylinders 45 and 52, as well as water inlet and outlet piping 71 and 72 which parallels the support columns of the converter, as shown in Fig. 6, is secured to such columns by bracing members 81. These members hold in position the stationary portions of the swivel joints that are in line with the axes of the converter trunnions 48.

What I claim is:

1. A slag skimmer or hold-back device for mounting on and use with a tiltable Bessemer converter; such device comprising a slag skimmer or hold-back member, mounting means for such member adapted to be pivotally connected to the converter shell adjacent the converter mouth, remotely controlled means for swinging such mounting means to move such skimmer member into and from the converter mouth, and remotely controlled means carried by such mounting

means for adjusting the position of such skimmer member with relation to the level of the metal content of the converter during pouring.

2. A slag skimmer or hold-back device for mounting on and use with a tiltable Bessemer converter; such device comprising a hollow skimmer member, mounting means for such member adapted to be pivotally connected to the converter shell adjacent the converter mouth, remotely controlled means for swinging such mounting means to move such skimmer member into and from the converter mouth, remotely controlled means for adjusting the position of such skimmer member with relation to the level of the metal content of the converter during pouring, and means for circulating cooling liquid through such skimmer member.

3. A slag skimmer or hold-back device for mounting on and use with a tiltable Bessemer converter; such device comprising a water cooled skimmer member, a mounting frame for such member adapted to be pivoted to the converter adjacent its mouth, remotely controlled fluid actuated means for swinging such mounting frame to move such skimmer member into and from the converter mouth, and remotely controlled fluid actuated means carried by such mounting means for adjusting the position of such skimmer member with relation to the level of the metal content of the converter during pouring.

4. A slag skimmer or hold-back device for mounting on and use with a tiltable Bessemer converter; such device comprising a hollow skimmer member, a support frame for such member including side members adapted to be pivotally connected to the converter shell adjacent the converter mouth, hollow means carried by such side members, rotatable with relation thereto and connecting with the interior of such skimmer member, means for circulating cooling liquid through such hollow means and such skimmer member, remotely controlled means for swinging such support frame to move such skimmer member into and from the converter mouth, and remotely controlled means carried by such mounting frame for adjusting the position of such skimmer member with relation to the level of the metal content of the converter during pouring.

5. A slag skimmer or hold-back device for mounting on and use with a tiltable Bessemer

converter; such device comprising a hollow skimmer member, a support frame for such skimmer member including side members adapted to be pivotally connected to the converter shell adjacent the converter mouth and tubular means carried by such side members, rotatable with relation thereto and having its interior connected with the interior of such skimmer member, remotely controlled means including an hydraulic cylinder for swinging such frame to move such skimmer member into and from the converter mouth, and remotely controlled means including an hydraulic cylinder carried by one of such side members for adjusting the position of such skimmer member with relation to the level of the metal content of the converter during pouring.

6. A slag skimmer or hold-back device for mounting on and use with a tiltable Bessemer converter; such device comprising a hollow skimmer member, a support frame for such member comprising side members adapted to be pivotally connected to the converter shell adjacent the converter mouth and a tubular end member carried by such side members, mounted for rotation with relation thereto and having branches which carry such skimmer member and connect the interior of such member to the interior of such tubular member, remotely controlled fluid actuated means for swinging such frame to move such end member to and from a position in front of the converter mouth with such skimmer member within the converter mouth, remotely controlled fluid actuated means carried by such support frame for adjusting the position of such skimmer member with relation to the level of the metal content of the converter during pouring, and means for flowing cooling water through such tubular end member, through its branches and through such skimmer member.
